(57) **CLAIM**

The ornamental design for a cleansing implement, as shown and described.

DESCRIPTION

FIG. 1 is a front perspective view of a cleansing implement showing our new design;

FIG. 2 is a top plan view thereof;

FIG. 3 is a bottom plan view thereof;

FIG. 4 is a front elevational view thereof;

FIG. 5 is a back elevational view thereof;

FIG. 6 is a right side elevational view thereof; and,

FIG. 7 is a left side elevational view thereof.

The broken lines immediately adjacent the shaded areas represent the bounds of the claimed design while the other broken lines are directed to environment and are for illustrative purposes only; the broken lines form no part of the claimed design.

1 Claim, 6 Drawing Sheets
